[57] CLAIM

The ornamental design for a combined display and packaging container for a shaving unit, substantially as shown and described.

DESCRIPTION

FIG. 1 is a bottom, front perspective view of a combined display and packaging container for a shaving unit showing my new design;

FIG. 2 is a front elevational view thereof;

FIG. 3 is a top plan view thereof;

FIG. 4 is an elevational view looking from the right of FIG. 2, the opposite side being substantially a mirror image thereof; and

FIG. 5 is a rear elevational view thereof.

The dash lines in FIGS. 1, 2 and 5 represent score lines.
